United States Patent Office.

EDMUND GREASLY, OF PHILADELPHIA, PENNSYLVANIA.

Design No. 4,386, dated October 4, 1870.

DESIGN FOR A KNITTED FABRIC.

The Schedule referred to in these Letters Patent and making part of the same.

I, EDMUND GREASLY, of Philadelphia, in the county of Philadelphia and State of Pennsylvania, have invented or produced a new and original Design for a Knitted Fabric, of which the following is a specification.

The nature of my design is fully represented in the accompanying drawing, to which reference is made.

The stripes F F, composed of any desired number of ribs, formed of interlocked cross-bars, as shown, alter-

nating with stripes composed of any desired number of ribs R R.

I claim—

The design for the knitted fabric described, and illustrated in and by the accompanying drawing.

EDMUND GREASLY.
